FOLDABLE FENCE

Frederic Martin Lewis, Belleville, Ontario, Canada, assignor to Jules Saman, Watertown, N. Y.

Application May 31, 1952, Serial No. 290,999

9 Claims. (Cl. 256—33)

1

This invention relates to fences of the type which are intended mainly for temporary use and which when not in use may be folded into compact form to facilitate the storage and handling of the same.

It is an object of this invention to provide a fence of this type which can be economically produced and which may be readily positioned in the ground and easily folded into compact form for storage or transport. It is also an object of this invention to provide a fence of this type which requires the minimum of welding to secure parts thereof together. A further object is to provide a fence comprising a plurality of U-shaped sections arranged with their legs extending horizontally and pivotally connected with adjacent sections and upright brace members welded or brazed to the legs intermediate of the ends thereof and having integral downwardly extending parts forming prongs which may be inserted into the ground.

Other objects and advantages will be apparent from the following description of one embodiment of the invention and the novel features will be particularly pointed out hereinafter in connection with the appended claims.

In the accompanying drawings:

Fig. 1 is a side elevation of a fence embodying this invention showing the parts of the same in operative positions.

Figs. 2, 3 and 4 are transverse sectional elevations thereof, on lines 2—2, 3—3 and 4—4 respectively of Fig. 1.

Fig. 5 is a horizontal sectional elevation thereof, on line 5—5, Fig. 1.

Fig. 6 is a bottom plan view of a section of fence showing the same in folded position for storage and transportation.

Fig. 7 is a side elevation, on a smaller scale, of a fence of modified construction.

Fences made in accordance with this invention comprise a plurality of sections hingedly connected in such manner that the fence when not in use can readily be folded into compact space. In the particular construction shown for this purpose, I have provided a plurality of U-shaped sections, each comprising an upright part 10 connected by two integral substantially horizontally extending legs 11 and 12. The units are preferably made of wire which can readily be bent into these U-shaped sections. The outer ends of the legs have loops 14 and 15 formed by bending the ends of the legs 11 and 12 back onto themselves and around the upright part or member 10 of an adjacent section. The loops, con-

sequently, form hinges and the upright parts 10 act as hinge pintles so that adjacent sections may readily be swung substantially into alignment with each other as shown in Fig. 1, or into substantially parallel relation to each other, as shown in Fig. 6. In order to make all of these sections alike, the legs 11 and 12 are bent to incline slightly toward each other so that the loops 14 and 15 will extend about an upright member 10 of an adjacent loop in close proximity to the legs 11 and 12 thereof.

In order to further assist in the folding of the fence sections into compact form, the U-shaped sections are so arranged that the loops 14 and 15 of one section extend horizontally in one direction from the legs 11 and 12 and the corresponding loops 14 and 15 of an adjacent section extend horizontally in opposite directions from the legs as clearly shown in Fig. 5. Consequently, the loops of alternate sections are offset horizontally in opposite directions, from the legs 11 and 12. By means of this arrangement of the loops, the adjacent sections of the fence may be folded so as to lie in close proximity to each other, thus economizing in the amount of space required to store the fence.

The legs 11 and 12 of each section of the fence are made of such length as to form a relatively large opening in each section, and in order to reduce this opening so that small animals cannot pass through the fence, I provide each section of the fence with an upright brace member 18 which is preferably made of the same type of wire as the U-shaped sections of the fence. This upright member may be formed of a separate piece of wire as shown in Figs. 1 to 6 or this member may be a continuation of one of the legs of the U-shaped section of the fence. These upright brace members serve several purposes. In the first place, they are rigidly secured to the legs 11 and 12 at their points of intersection. Preferably the upright members are secured to the legs of the sections by means of welding or brazing, as indicated at 19, Fig. 3. By securing the upright member 18 to the legs 11 and 12 of the sections, these sections are greatly reinforced and strengthened so that there is very little tendency of the legs to be bent out of shape toward or away from each other. The upright members are also provided with integral parts extending downwardly from the lower legs 12 of the sections, thus forming prongs or projections 20 which act as spikes to be driven into the ground for holding the fence in the desired position.

The upper ends of the upright members 18

preferably also extend materially above the upper legs 11 of the fence sections. These upwardly extending portions 22 may be bent over in any desired manner, for example, into approximately semi-circular form as shown in Fig. 1, so that the outer end of each of the bent-over sections 22 is substantially in alignment with the upright part 10 of a fence section. These parts 22, consequently, add to the effective height of the fence and by bending these parts over so that they appear to be a continuation of the upright parts 10 of the sections, a pleasing effect is obtained and also the ends of the parts 22 which may be somewhat sharp, are so positioned that they are not apt to injure any one coming in contact with the same or to tear clothes of a person walking near the fence.

The end of a fence section may terminate in a shorter upright end bar 25 as clearly shown in Fig. 1. In order to hold this end bar in place on the fence, one end thereof, for example, the upper end, as shown in Figs. 1 and 2, may be looped over as shown at 27, Fig. 2, about a loop 14.

The fence described, in addition to being readily foldable into compact form also has the advantage that it is easy to construct in that each unit or section consists of only two parts, namely, a U-shaped member and a brace member. These parts are readily assembled by means of welding or brazing at two points. The legs of the U-shaped parts are reinforced by the brace members and also by the hinged connections of the legs with the upright members 10 of adjacent sections, thus resulting in a strong and rigid fence.

In the modified construction shown in Fig. 7, each section or part of the fence is made of a single piece of wire. In this construction, the U-shaped sections are provided with upright members 30 terminating in upper legs 31. The leg 31 of each U-shaped section is looped around the upper portion of the upright member 30 of an adjacent U-shaped section, as shown at 32, as is done in the construction shown in Figs. 1 to 6. In the construction of Fig. 7, however, the wire, after forming the loop 32, is bent to form the upright member connecting the legs of the U and for this purpose, the wire after being looped is bent to form a part 33 extending above the upper leg of the U-shaped section and is then bent downwardly to form an upright member 34 corresponding to the member 10 shown in Figs. 1 to 6, including the downwardly extending prong or spike 35, which may be inserted into the ground. The upright part 34 is welded or brazed to the legs of the U-shaped member at the points of intersection of the same. The fence shown in this construction may be folded in the same manner as the one shown in Figs. 1 to 6, and has all the advantages of that construction.

It will be understood that various changes in the details, materials, and arrangements of parts which have been herein described and illustrated in order to explain the nature of the invention, may be made by those skilled in the art within the principle and scope of the invention, as expressed in the appended claims.

I claim as my invention:

1. A foldable fence comprising a plurality of U-shaped sections, each having its legs arranged substantially horizontally one above the other and connected by an integral upright member, the outer ends of the legs of the sections having bends to form loops, the loops of one section extending about the upright member of an adja-

cent section, and upright brace members secured to said legs intermediate of the ends thereof for supporting said legs in substantially parallel relation to each other.

2. A foldable fence according to claim 1, in which said upright brace member constitutes an integral extension of one of said loops.

3. A foldable fence comprising a plurality of U-shaped sections, each having its legs arranged substantially horizontally one above the other and connected by an integral upright member, the free ends of the legs of the sections being provided with bends to form loops, the loops of one section extending about the upright member of an adjacent section, and upright brace members secured to said legs intermediate of the ends thereof for supporting said legs in spaced relation to each other, said brace members having integral parts extending below the lower legs of said sections to form prongs that may be inserted into the ground to support the fence in upright position.

4. A foldable fence comprising a plurality of U-shaped sections, each having its legs arranged substantially horizontally one above the other and connected by an integral upright member, the free ends of the legs of the sections having bends to form loops, the loops of one section extending about the upright member of an adjacent section, and upright brace members secured to said legs intermediate of the ends thereof for supporting said legs in their horizontal positions, said brace members having integral parts extending upwardly above the upper legs of said sections to increase the height of said fence.

5. A foldable fence comprising a plurality of U-shaped sections, each having its legs arranged substantially horizontally one above the other and connected by an integral upright member, the free ends of the legs of the sections being provided with integral loops, the loops of one section extending about the upright member of an adjacent section, and upright brace members secured to said legs intermediate of the ends thereof for supporting said legs in their spaced relation to each other, said brace members having integral parts extending upwardly above the upper legs of said sections, said upwardly extending parts being curved through about 180 degrees with their free ends terminating adjacent to said upper legs and said upright members of said sections.

6. A foldable fence comprising a plurality of U-shaped sections, each having its legs arranged horizontally one above the other and connected by an integral upright member, the free ends of the legs of the sections having bends to form loops, the loops of one section extending about the upright member of an adjacent section, and upright brace members secured to said legs intermediate of the ends thereof for supporting said legs in spaced relation to each other, said brace members having integral parts extending below the lower legs of said sections to form prongs that may be inserted into the ground to support the fence in upright position, said brace members also having parts extending upwardly above the upper legs of said sections and bent through approximately 180 degrees with their free ends extending into close proximity to said upper legs.

7. A foldable fence comprising a plurality of U-shaped sections, each having its legs arranged substantially horizontally one above the other and connected by an integral upright member, the free ends of the legs of the sections having

bends to form loops, the loops of one section extending about the upright member of an adjacent section, upright brace members secured to said legs intermediate of the ends thereof for supporting said legs in their spaced relation to each other, said brace members having integral parts extending upwardly above the upper legs of said sections to increase the height of said fence, and welded connections between said arms and said brace members.

8. A foldable fence comprising a plurality of U-shaped sections, each having its legs arranged substantially horizontally one above the other and connected by an integral upright member, the free ends of the legs of the sections having bends to form loops, the loops of one section extending about the upright member of an adjacent section, and upright brace members secured to said legs intermediate of the ends thereof for supporting said legs in their spaced relation to each other, the loops of alternate adjacent sections extending approximately horizontally in opposite directions from said legs, to enable said units when folded to lie in approximately parallel planes.

15

20

25

9. A foldable fence comprising a plurality of U-shaped sections, each having its legs arranged substantially horizontally one above the other and connected by an integral upright member, the free ends of the legs of the sections having bends to form loops, the loops of one section extending about the upright member of an adjacent section, the upper leg, after being looped about the upright member of and adjacent section extending back on itself and upwardly over said U-shaped section and then downwardly to intersect said legs to form a brace member, and means for securing said brace member to said legs.
